[57] CLAIM

The ornamental design for a lighted cross guard sign, as shown and described.

DESCRIPTION

FIG. 1 is a top, front, left side perspective view of a lighted cross guard sign showing my new design;

FIG. 2 is a top plan view thereof;

FIG. 3 is a left side elevational view thereof, the right side being a mirror image except for the omission of the switch.

The octagonal sign housing is translucent, the rear being flat and plain.

FIG. 1

FIG. 2

FIG. 3
